UNITED STATES PATENT OFFICE.

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI.

TRACK FOR GYMNASIUM CLIMBING POLES.

Application filed April 21, 1922. Serial No. 555,879.

To all whom it may concern:

Be it known that I, FRANK ALBACH, a citizen of the United States of America, residing in the city of St. Louis and State of Missouri, have invented certain new and useful Improvements in Tracks for Gymnasium Climbing Poles, of which the following is a specification.

This invention relates to overhead supporting tracks for the plurality of depending climbing poles used in gymnasium exercises, and has for its various objects:

To provide a structural formation and combination of parts in which a swinging end section of an overhead or trolley track is adapted to receive the series of depending climbing poles of the apparatus in closely arranged relation, when not required for use, to be swung against the wall of the building out of the way and with the room clear for other exercises.

To provide means whereby the swinging track section is guided, supported and locked in longitudinal alignment with the fixed or main track section.

To provide automatic means for preventing the unlocking of the track sections until all of the suspension trucks of the climbing poles are wholly within or upon the swinging track section.

To provide means whereby the series of suspension trucks are automatically confined in the swinging track section, as the same swings away from the fixed track section, with such confinement prevailing until the track sections are brought into proper alignment, when such confinement is automatically released to permit of the proper extension and separation of the trucks and climbing poles for actual use.

To provide a structural formation and combination of parts by which a uniform spacing of the series of climbing poles in proper separated condition is attained with an automatic locking of the parts in such condition, all as will hereinafter more fully appear.

In the accompanying drawings:

Fig. 1, is a plan view illustrating the general arrangement of parts in the present invention, the respective positions of the swinging track section being shown in full and in dotted lines.

Fig. 2, is an elevation of the same, the respective positions of the climbing poles

having a like showing in full and dotted lines.

Fig. 3, is a detail perspective view of the free end of the swinging track section and the coupling head mounted thereon.

Fig. 4, is a like view of the adjacent end of the fixed track section and the companion coupling head thereof.

Fig. 5, is a detail perspective view of the end trolley truck or carriage of the series.

Fig. 6, is a detail side elevation of the coupling heads of the two track sections in an engaged condition.

Fig. 7, is a horizontal section of the same on line 7—7, Fig. 6.

Fig. 8, is a transverse section on line 8—8, Fig. 6.

Fig. 9, is a similar view on line 9—9, Fig. 6.

Fig. 10, is a detail longitudinal sectional elevation showing the end truck or carriage and latch mechanism by which the same is locked in place with the climbing poles properly spaced for actual use.

Fig. 11, is a side elevation of one of the series of trucks or carriages other than the end truck shown in Fig. 10.

Fig. 12, is a detail transverse sectional elevation on line 12—12, Fig. 10.

Like reference numerals indicate like parts in the several views.

Referring to the drawings, 1 designates the main stationary section of the trolley track fixedly secured to an overhead girder 2 or like support in the ceiling of the building. Said track section is preferably of the rectangular tubular form shown, and having a central slot or passage the length of its bottom web, with the sides of said slot formed with upstanding flanges 3 to afford stiffness and provide side channels or track ways for the wheels of the series of trucks or carriages hereinafter described.

4 designates the companion swinging section of the track, of a similar formation to that of the stationary track section 1 above described, and having a tubular vertically depending extension 5 by which it is pivotally supported in bearing brackets 6 on the side wall of the room, the portions of the track section being braced in proper relation by diagonal struts 6' or other usual means.

7 designates the series of depending climbing poles, the upper ends of which are piv-

110

totally secured to individual trucks or carriages now to be described.

With the exception of the end carriage or truck of the series which is next adjacent to the remote end of the stationary track section 1 when the apparatus is arranged for actual use, the remainder of the series of trucks are of a counter-part construction and preferably of the detail formation and arrangement illustrated in Fig. 11 in which:—

8 designates the main body of the truck carrying a pair of transverse axles upon the ends of which are mounted track wheels 9 adapted to roll along the side channels or trackways of the track sections 1 and 4 heretofore described.

10 designates a central web of a plate form depending from the truck body 8 and provided at its lower end with an eye or loop 20 11 for pivotal engagement with an open eye or hook on the end of a socket sleeve fixedly attached to the upper end of a climbing pole 7.

12 designates sections of chain or like flexible means extending between adjacent truck bodies 8 and adapted to prevent an undue separation between said truck bodies and attain an even spacing of the series of climbing poles 7 when the parts are positioned 30 for use.

13 and 14 designate bumper heads on the ends of the truck bodies 8, which in the operation of pulling the series of trucks and climbing poles carried thereby into an inactive position by the pull rope or connection hereinafter described, are adapted by contact of the forward bumper of one truck with the rear bumper to a truck in advance, to move the series of trucks along the track sections 1 and 4, and attain a uniform close relation of the same on the swinging track section 4 without any tendency to one truck and pole moving past another.

The end truck or carriage above referred 45 to, and which is illustrated in Figs. 5, 8 and 10, is of the same general construction as that above described, with the addition of means and mechanisms as follows:—

15 designates an angle lever pivoted at an 50 end of the truck body 8', with its longitudinal arm having a hooked end 16, adapted for engagement with a similarly formed latch block 17 secured in the end of the stationary track section 1, and adapted to prevent a 55 retrograde movement of the trucks until a release of said engagement is effected. The vertical arm of the lever 15 is attached to one end of a flexible connection or pull rope 18, which extends horizontally along the stationary and swinging track sections 1, 4, and 60 down through the tubular pivot extension 5 of the track section 4 within convenient reach of the operator, so that he may pull the entire series of trucks wholly into or 65 upon the swinging track section 4, when it

is desired to move the climbing poles out of the way after the use of the same.

19 designates a lateral lug on the lower part of the web 10 of the truck body 8' for operative engagement with the hereinafter 70 described auxiliary locking mechanisms of the track sections.

20 designates a longitudinal shoe secured to the lower portion of the web 10 aforesaid and having a tapering end so as to readily 75 pass between the hereinafter described pair of positioning rollers on the swinging track section 4 and adapted to hold the truck from any swaying movement while the aforesaid lateral lug 19 is functioning.

21 and 22 designates companion coupling heads of a rectangular yoke form, fitted to the adjacent ends of the track sections 1 and 4 aforesaid, and having slots or passages in their bottom webs registering with the slots 85 or passages of said track sections.

In the preferred construction shown, the end of the coupling head 21 extends a distance beyond the end of the stationary track section 1 to which it is attached, and the extended portion has its forward side wall removed, to provide an entry way for the end of the swinging track section 4, which for such purpose extends a distance beyond its coupling head 22 as illustrated in Figs. 2 95 and 7. In such construction, with the end of the swinging track section 4 in place in the aforesaid extension of the coupling 21, said track section 4 is substantially supported in aligned relation to the companion stationery track section 1.

23 designates an inclined lip on the forward end of the bottom web of the aforesaid extension of the coupling head 21, adapted to guide the swinging track member 105 4 into place.

24 designates a combined inclined strike rail and recessed keeper on the forward side of the coupling head 21 adjacent to the open side of its extension and adapted for operative and holding engagement with the main spring latch bolt hereinafter described.

25 designates a longitudinal lug on the forward side of the coupling head 21 for operative engagement with the transversely 115 moving gate bar or bolt hereinafter described.

26 designates the main latch bolt of the present construction, moving longitudinally in guides on the forward side of the coupling head 22 aforesaid, and operated in one direction by a spring 27, to engagement with the strike rail and keeper 24 aforesaid.

28 designates a bell crank lever journalled on the coupling head 22 in adjacent relation 125 to the latch bolt 26, with one of its arms in operative engagement with said latch bolt to impart a retractile or release movement thereto against the resilient stress of the spring 27 aforesaid. The other arm of the 130

bell crank lever 28 has a shackle connection with a pull rope 29 by which the lever and latch bar are operated, with said pull rope adapted to pull the swinging track section 4 out of line with the stationary track section 1.

30 designates an auxiliary latch bolt having movement in right angle relation to the main latch bolt 26 and adapted to engage in 10 a recess in a side face of said bolt 26 and lock it against movement until a release of such engagement is automatically effected by means hereinafter described.

31 designates a spring, the tendency of 15 which is to move the auxiliary latch bolt 30 out of the above described locking engagement with the main latch bolt.

32 designates a semi-rotary cam ring associated with the auxiliary latch bolt 30, and 20 having a cam formation on its upper end adapted for operative engagement with a lateral stud or projection 33 on said latch bolt, and adapted in one position to move and hold the latch bolt 30 in locking engagement with the main latch bolt 26 aforesaid. In the other position of the ring 32 its cam formation permits a descent of the stud 33 and auxiliary latch bolt 30 under the stress of the spring 31 and release the above described locking engagement of the latch bolts.

34 designates a forked arm fixed on the cam ring 32 and extending laterally into the path of the heretofore described lateral lug 35 19 of the end truck body 8', and in the preferred construction herein illustrated, the functioning of the parts is as follows:—

As the end truck 8' with its lug 19 moves from the stationary track section 1 onto the 40 swinging track section 4, the lug 19 contacts with one branch of the forked arm 34 to impart a semi-rotary movement to the cam ring 32, to in turn permit a downward movement of the auxiliary latch bolt 30 from an existing locking engagement with the main latch bolt 26. With such release 45 of the main latch bolt 26, the manual retraction of the same can be effected, to permit the swinging of the track section 4 into a position against the wall of the building. In such operation the presence of all the 50 trucks 8, 8' in the swinging track section 4 is insured.

35 designates a pair of positioning rollers 55 secured to the under face of the coupling head 22, at the sides of its longitudinal slot or passage and in proximity to the auxiliary latch bolt 30 and the operating mechanism thereof. The rollers 35 are adapted to have 60 bearing against the heretofore described longitudinal shoe 20 of the end truck 8' to hold and guide the same against lateral tilt during the operative engagement of the lug 19 with the operating mechanism of the auxiliary bolt 30 above described.

36 designates a gate or bar arranged to have movement across the interior of the coupling head 22 and act as a barrier therefor. In the preferred construction shown, the gate or bar 36 has sliding movement in 70 guides on the end of the coupling head 22, and has movement in a direction across the interior of the head by an associated spring 37.

38 designates a stud or lug on the side of 75 the gate or bar 36, adapted for abutment against the heretofore described lug 25 of the coupling head 21 on the fixed track section 1, so that when the coupling head 22 of the swinging track section 4 moves to an 80 aligned position with the stationary track section 1, the gate or bar 36 will be held stationary while the coupling head 22 of the swinging track section 4 upon which it is mounted completes its movement into longitudinal alignment with the coupling head 21 with its interior left free and unobstructed by said gate or bar. In like manner an initial movement of the swinging track section 4 away from the stationary track section 1 85 permits the gate or bar 36 to resume its position across the interior of the coupling head 22 into its normal condition as a barrier and prevent any accidental retrograde movement of the pole carrying trucks 8, 8' 90 occupying said swinging track section 4.

The operation and functioning of the various parts and mechanisms of the present construction have been set forth in connection with the description of the same, the 100 general co-operation of the features and mechanisms is as follows:—

With the track sections 1 and 4 locked in an aligned relation by the main latch bolt 26, and said latch bolt in turn locked against 105 movement by the auxiliary latch bolt 30 the series of climbing poles 7 and their trucks 8, 8' can be spaced along the track sections for use in the required gymnastic exercises, and such spaced relation will be maintained 110 by an engagement of the bell crank lever 15 and its hook 16 of the end truck 8' with the latch block or lug 17 of the stationary track section 1.

After such use of the climbing poles, the 115 same are moved against the wall of the building and out of the way by the following series of operations:—

By a pulling action on the part of the attendant upon the pull rope 18 the hook 16 120 of the bell crank lever 15 is released from its described engagement with the latch lug 17, and a continued pull by the attendant on the pull rope 18 will move the series of pole carrying trucks 8, 8' along the main track 125 section 1 and wholly into the swinging track section 4. With the movement of the last or end track 8' into the track section 4 the auxiliary latch bolt 30 is automatically moved into its release position in the manner here- 130

tofore described leaving the main latch bolt 26 free to be released in a succeeding operation, to-wit:

- 5 By a pulling action on the part of the attendant upon the pull rope 29 the main latch bolt 26 is moved and held out of its engagement with the coupling head 21 of the stationary track section 1, after which a continued pull on the rope 29 may be used to 10 move said swinging track section and the contained pole carrying trucks into a position against the wall of the building and out of the way until again required. With an initial movement of the track section 4 away 15 from the stationary track section 1, the gate or bar 36 moves automatically across the interior of the coupling head 22, to prevent accidental escape of the trucks while the swinging track section 4 remains out of 20 alignment with said stationary track section.

Having thus fully described my invention what I claim as new and desire to secure by Letters Patent, is:—

- 25 1. In a pole climbing apparatus, the combination of a stationary track section, a swinging track section adapted to move into aligned relation with the stationary section, a latch mechanism adapted to lock said sections in aligned relation, a series of trucks 30 having movement upon said tracks, means for limiting the degree of separation of said trucks, the swinging track section having a length sufficient to store the series of trucks 35 in a closely arranged condition, and a series of climbing poles suspended from said trucks.
2. In a pole climbing apparatus, the combination of a stationary track section, a 40 swinging track section adapted to move into aligned relation with the stationary section, a main latch mechanism adapted to lock said sections in aligned relation, an auxiliary latch mechanism adapted to lock the main 45 latch mechanism in an engaged condition, a series of trucks having movement on said tracks, means on one of said tracks for operating said auxiliary latch mechanism, and a series of climbing poles suspended 50 from said trucks.

3. In a pole climbing apparatus, the combination of a stationary track section, a swinging track section adapted to move into aligned relation with the stationary section, a latch mechanism adapted to lock said sections in aligned relation, a series of trucks having movement on said track sections, a movable bar or gate arranged transversely of and adapted to move across the end 55 swinging track section as the same swings away from its alignment with the stationary track section, and a series of climbing poles suspended from said trucks.

4. In a pole climbing apparatus, the combination of a stationary track section, a

swinging track section adapted to move into aligned relation with the stationary section, a latch mechanism adapted to lock said sections in aligned relation, a series of trucks having movement on said track sections, a latch lever carried on an end truck of the series, a latch bar at the remote end of the stationary track section for engagement with said latch lever, a flexible pull connection attached to said latch lever, and a series of climbing poles suspended from said trucks.

5. In a pole climbing apparatus, the combination of a stationary track section, a swinging track section adapted to move into aligned relation with the stationary section, a latch mechanism adapted to lock said sections in aligned relation, a series of trucks having movement on said track sections, a movable bar or gate arranged transversely of and adapted to move across the end of the swinging track section as the same swings away from its alignment with the stationary track section, a latch bar carried on an end truck of the series, a latch bar at the remote end of the stationary track section for engagement with said latch lever, a flexible pull connection attached to said latch lever, and a series of climbing poles suspended from said trucks.

6. In a pole climbing apparatus, the combination of a stationary track section, a swinging track section adapted to move into aligned relation with the stationary section, a latch mechanism adapted to lock said sections in aligned relation, a series of trucks having movement on said track sections, a latch bar or gate slidably mounted in the end of the swinging track section and adapted to move across the same, a spring tending to move the bar or gate in one direction, means on the stationary track section for moving the bar or gate in the other direction, and a series of climbing poles suspended from said trucks.

7. In a pole climbing apparatus, the combination of a stationary track section, a swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, and a flexible pull connection attached to an end truck of the series and extending longitudinally within the track sections and down through the vertical extension of the swinging track section.

8. In a pole climbing apparatus, the combination of a stationary track section, a

- swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, means for limiting the separation of the trucks, and a flexible pull connection attached to the end truck of the series and extending longitudinally within the track sections and down through the vertical extension of the swinging track section. 70
9. In a pole climbing apparatus, the combination of a stationary track section, a swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, and a flexible pull connection attached to an end truck of the series and extending longitudinally within the track sections and down through the vertical extension of the swinging track section. 75
10. In a pole climbing apparatus, the combination of a stationary track section, a swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, and a flexible pull connection attached to an end truck of the series and extending longitudinally within the track sections and down through the vertical extension of the swinging track section. 80
11. In a pole climbing apparatus, the combination of a stationary track section, a swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, and a flexible pull connection attached to an end truck of the series and extending longitudinally within the track sections and down through the vertical extension of the swinging track section. 85
12. In a pole climbing apparatus, the combination of a stationary track section, a swinging track section adapted to move into aligned relation with said stationary section, the track sections having a longitudinally slotted formation, a tubular vertical extension on an end of the swinging track section adapted for pivotal engagement with brackets on the wall of a building, a latch mechanism adapted to lock the track sections in aligned relation, a series of trucks moving in said track sections, a series of climbing poles suspended from said trucks, and a flexible pull connection attached to an end truck of the series and extending longitudinally within the track sections and down through the vertical extension of the swinging track section. 90
13. In a pole climbing apparatus, the combination of a stationary track section, a swinging track section adapted to move into aligned relation with the stationary section, a series of trucks having movement on said tracks, means for limiting the extent of separation of said trucks, the swinging track section having a length sufficient to store the series of trucks in a closely arranged condition, a latch bolt adapted to lock said sections in aligned relation, a bell crank lever operatively connected to said latch bolt, and a flexible pull connection attached to said lever. 95
14. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 100
15. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 105
16. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 110
17. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 115
18. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 120
19. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 125
20. In a pole climbing apparatus, the combination of a stationary track section, a swinging track section adapted to move into aligned relation with the stationary section, a latch mechanism adapted to lock said sections in aligned relation, a series of trucks having movement upon said tracks, means for limiting the degree of separation 130

of said trucks, bumper heads on the end of the trucks adapted to impose uniform spacing on said trucks in their movement along the track sections, the swinging track section having a length sufficient to store the series of trucks in a closely arranged condition, and a series of climbing poles suspended from said trucks.

15. In a pole climbing apparatus, the combination of a stationary track section, a swinging track section adapted to move into aligned relation with the stationary section, a main latch mechanism adapted to lock said sections in aligned relation, an auxiliary latch mechanism adapted to lock the main latch mechanism in an engaged condition, the same comprising a latch bolt, a spring tending to move said bolt in one direction and a semi-rotary cam adapted to move said bolt in the other direction, a series of trucks having movement on the track sections aforesaid, a series of climbing poles suspended from said trucks, and operative connections between said cam and an end truck of the series for automatically turning said cam.

16. In a pole climbing apparatus, the combination of a stationary track section, a swinging track section adapted to move into aligned relation with the stationary section, a main latch mechanism adapted to lock said sections in aligned relation, an auxiliary latch mechanism adapted to lock the main latch mechanism in an engaged condition, the same comprising a latch bolt, a spring tending to move said bolt in one direction and a semi-rotary cam adapted

to move said bolt in the other direction, a series of trucks having movement on the track sections aforesaid, a series of climbing poles suspended from said trucks, and operative connections between said cam and an end truck of the series for automatically turning said cam, the same comprising a forked arm extending laterally from said cam, and a lateral lug on said end truck adapted for intermittent operative engagement with said cam arm.

17. In a pole climbing apparatus, the combination of a stationary track section, a swinging track section adapted to move into aligned relation with the stationary section, a main latch mechanism adapted to lock said sections in aligned relation, an auxiliary latch mechanism adapted to lock the main latch mechanism in an engaged condition the same comprising a latch bolt, a spring tending to move said bolt in one direction and semi-rotary cam adapted to move said bolt in the other direction, a series of trucks having movement on the track sections aforesaid, a series of climbing poles suspended from said trucks, operative connections between said cam and an end truck of the series for automatically turning said cam, positioning rollers mounted on the underside of the swinging track section, and a longitudinal shoe on the end truck aforesaid, adapted to move between said rollers and hold the truck against lateral sway.

Signed at St. Louis, Missouri, this 18th day of April A. D. 1922.

FRANK ALBACH.
